UNITED STATES PATENT OFFICE.

WILLIAM S. ROBBINS, OF NEW BEDFORD, MASSACHUSETTS.

GRINDING-MACHINE.

SPECIFICATION forming part of Letters Patent No. 401,212, dated April 9, 1889.

Application filed July 20, 1888. Serial No. 280,578. (No model.)

To all whom it may concern:

Be it known that I, WILLIAM S. ROBBINS, a citizen of the United States, residing at New Bedford, in the county of Bristol and 5 State of Massachusetts, have invented a new and useful Improvement in Grinding-Machines, of which the following is a specification.

In the accompanying drawings, Figure 1 is 10 a side elevation of the machine, and Fig. 2 is a view showing the detail of some of the working parts.

The band-wheels *b* and *c* are journaled on 15 studs projecting from the side of the standard *a*, and are connected by a band, *d*. The tube *g*, having weight *h*, is pivoted to the top of the standard *a* at *f*. The rod *e* is placed within the tube *g*, and secured by the thumb-screw *i*.

20 The outer end of the rod *e* is provided with a fork, *x*, between which is hung the yoke *m* by the shaft of the band-wheel *k*. The rod *p* is journaled in the yoke *m* and its end provided with a bevel-gear, *o*, which meshes with

25 a bevel-gear on the shaft of the band-wheel *k*. The lower end of the rod *p* is journaled in

the box *q*, and is provided with a bevel-gear, *r*, which meshes with the bevel-gear *s* on the shaft *v*, on which shaft is mounted the emery-wheel *t*. The box *q* is provided with a handle, 30 *z*, by means of which the work of the emery-wheel is controlled. The band-wheel *c* has a double face, in order to take the band from the wheel *b*, and also carry the band to the wheel *k*.

35

What I claim is—

In a grinding-machine, the combination of the standard *a*, band-wheels *b* and *c*, pivoted tube *g*, rod *e*, provided with fork *x*, the shaft *n*, provided with band-wheel *k*, and bevel-gear 40 meshing with bevel-gear on rod *p* and pivoting the fork *x* and yoke *m* together, the rod *p*, journaled in yoke *m* and box *q*, and provided with bevel-gears *o* and *r*, the box *q* provided with handle *z*, having journaled in it 45 the shaft *v*, having mounted on it the emery-wheel *t*, and bevel-gear *s*, all as shown and described.

WILLIAM S. ROBBINS.
